UNITED STATES PATENT OFFICE

JAMES L. WATERBURY, OF SPRINGFIELD, OHIO

HEATING AND VENTILATING APPARATUS

Application filed January 23, 1931. Serial No. 510,656.

The present invention relates to heating and ventilating apparatus, and more particularly to the means for inducing a draft or circuit of air through a building and heating flues of a dwelling or the like.

An object of this invention is to provide a device, which may be installed in a dwelling or other house for operating in connection with the heating plant of the house to set up or force air currents through the house, so that the cool air may be more rapidly returned to the furnace or heater and the warm air be more evenly and rapidly diffused throughout the interior of the house.

Another object of the invention is to provide an air current impelling means, which includes an electric motor and a fan so mounted that the vibration of the apparatus when running will not be transmitted to the house structure and also the noise incident to the running of the motor and fan will be reduced to a minimum and the noise vibrations be arrested through the medium of sound non-conducting insulators.

The invention also aims to provide a grating for insertion in the floor of the building and through which the air is adapted to be forced by the device, and to provide an improved mounting and connection between the floor and the grating and the grating and the fan, so that the entire device may be easily and quickly installed as a unit either in the floor of a house adjacent the heater, or in the upper part of a pipeless furnace for assisting and forcing the circulation of air through the furnace and through the house.

The invention still further aims to provide an improved mounting for the motor for the purpose of absorbing vibration and noise and for yieldably supporting the motor against shock and the like, which would otherwise be imposed on the apparatus tending to disturb its adjustment and attachment to the grating or adjacent parts of the building.

With the foregoing and other objects in view, the invention will be more fully described hereinafter, and will be more particularly pointed out in the claims appended hereto.

In the drawings, wherein like symbols re-

fer to like or corresponding parts throughout the several views.

Figure 1 is a vertical section taken through a pipeless furnace, shown diagrammatically and in which is mounted an improved draft impelling device constructed according to this invention.

Figure 2 is a fragmentary enlarged section taken through the device in its position with respect to one side of the wall of the furnace.

Figure 3 is a sectional view taken through a portion of the flooring of a building, showing a slightly modified form of the device applied thereto.

Figure 4 is a fragmentary section of a modified form of grating and motor supporting connection, and

Figure 5 is a fragmentary sectional view through a portion of a modified form of grating and suspension means for the motor and the fan.

Referring to the drawings, 10 designates the outer wall of a pipeless furnace and 11 an inner wall or partition, which is concentrically spaced within the wall 10 and which extends from approximately the upper end of the wall 10 to a point spaced above the lower end or bottom 12 of the furnace.

Such arrangement provides a cold air passage 13 about the inner wall of the furnace and which opens through the top of the furnace to receive cold air from the room or compartment above the furnace, the cold air being conducted downwardly through the passage 13 and about the lower end of the partition 11, and then upwardly into contact with the heating drum 14, and combustion chamber 15 which are supported upon the ash pit 16, as diagrammatically shown.

The air which is heated in the inner chamber contained within the partition 11 rises upwardly through the top of the furnace and through a grating 17 seated in the floor or over the top of the furnace to permit the warm air to rise through the central flue or portion of the furnace. The cooler air in the room accumulates in the bottom and is drawn toward the upper end of the furnace 10 by the ascending heated air from the furnace, the cooler air entering downwardly through

the top of the passage 13 where it is conducted to the heating chamber and is thence returned to the room or compartment of the building.

5 As is shown in Figure 2, the grating 17 is provided with bracket plates 18 secured by bolts 19 or the like against the under side of the grating 17, and the brackets 18 are provided with downwardly extending hooks 20 upon which coil springs 21 are engaged for supporting the impelling device of this invention.

There is provided a spider or frame consisting of a ring 27 having a plurality of radiating arms 22, which arms are mounted on the lower ends of springs 21. These arms carry a circular shield 23 adapted to protect the springs 21 against hot air which is impelled by a fan 24, which is disposed in the upper portion of the hot air passage formed by the inner wall 11. The fan 24 is mounted on the upper end of the shaft 25 of an electric motor 30. The ring 27 supports an annular resilient ring 28 on which are hung supporting hooks or members 29. The motor is clamped to the lower ends of these hooks by bolts 31 which pass through ears on the lower inturned portions of the hooks and also through cross bars 31' extending over the upper end of the motor. The spider serves to support the motor and by use of the resilient ring 28 all vibration and noise produced by the operation of the motor is stopped and cushioned and consequently the operation of the impelling device can hardly be detected when operated in a dwelling. The motor 30 is surrounded by a hood 32, which is secured to the upper ends of the bolts 31 and which is spaced about the motor a distance sufficient 40 to provide an upwardly directed annular passage about the motor.

The casing 32 in its top has an opening adapted to directly open centrally above the motor 30, and an annular wall or flange 34 is provided on the hood 32 and extends upwardly into proximity to the under side of the fan 24, so that the latter may be operated not only to raise the heated air outside of the hood 32, through the top of the furnace 10, but the fan 24 also draws a quantity of cold air upwardly through the middle of the hood 32 and about the motor 30. Such action commingles the cold air with the warm air so as to produce a more even temperature in the house, and also produces a continuous current of relatively cool air against and about the motor 30 to protect the latter against the heat, which is produced in the top of the pipeless furnace.

60 According to the installation shown in Figures 1 and 2, the hood 32 of the motor fan is coupled to the upturned end of an air duct 35, which first extends downwardly from the hood 32, and thence laterally thereof to provide a hollow arm 36 which passes between

and in spaced relation from the springs 21 and the spider arms 22. The hollow extension 36 extends upwardly and outwardly from the lower casing part 35 and is provided upon its upper end with a bellows connecting member 37 adapted for connection at its free end with a flange or nipple 38 formed upon the inner wall 11 of the furnace near the top thereof, the wall 11 being recessed within the flange 38 to provide an opening through which cold air passing downwardly into the passage 13 may be carried off to the fan. This cold air is thus carried directly to the fan and forced upwardly and outwardly by means of the fan to commingle with the heated air outside of the hood 32.

70 The natural circulation of the air is thus augmented not only by the impelling device, which naturally forces the circuit, but also by admixing a portion of the returning cold air with the outgoing heated air from the furnace, so as to moderate the heated air to such an extent that the entire cubic contents of the building is maintained at substantially a uniform temperature.

75 In such cases where it is desired to produce a forced circulation of air in connection with a hot air furnace of any type, the floor 39 of the building may be recessed to receive a grating 40, which opens through the floor between a pair of joists 41. The joists 41 are utilized for supporting a pair of brackets 42, which are secured against the inner opposite faces of the joists in proximity to the grating 40 and which have hooks 43 from which are suspended springs 44 carrying upon their lower ends the arms of a spider 45, which have cushioning blocks 46 there beneath, as shown in Figure 3, so as to not only yieldingly support the spider 45, but also deaden or arrest noise vibrations incident to the operation of a motor 47, which is seated in the spider 45 by means of the resilient ring 28. In this case the motor 47 may be provided with a fan 48, the blades of which are so set as to effect a downward suction of air through the grating 40 from the space above the floor 39 down through the floor and into an air receiving casing or duct 49, which may be placed in communication with the cold air intake of a furnace or the like.

80 This type of device may be readily installed in a dwelling or other building without disturbing the installation of the hot air heating unit.

85 In Figure 4 a slight modification is shown wherein the floor 50 has mortised or seated in its upper face a flange 51 of a depending shoulder or seat plate 52 having a horizontal portion 53, which projects inwardly and in downwardly spaced relation with respect to the flange 51 to accommodate a resilient block 54 of rubber or the like and upon which a grating 55 is seated. This block 54 is utilized 90 for supporting the upper end of a motor 105

5 suspending spring 56 and is apertured to receive the upwardly extending extremity 57 of the spring which may be enlarged or headed in any suitable manner, as shown in Figure 4 to hold the end 57 from moving downwardly through the block 54.

10 The modification shown in Figure 5 discloses a grating 58 to the under side of which may be integrally cast or formed a bracket 59 carrying a hook 60 disposed beneath the grating 58 to receive the upper end of a motor supporting spring 61.

15 In all forms of the invention it will be noted that the electric motor and its fan are mounted yieldingly upon springs or the like so as to absorb vibration incident to the running of the motor and the fan, and are also mounted upon resilient elements adapted to absorb or arrest sound vibrations, so that 20 the motor and fan may be run without producing noise or vibration in the building.

25 It will also be noted that the devices of this invention are of such a nature that they may be quickly and easily installed in a pipeless furnace or in a house without modifying either the furnace or the house to any appreciable extent.

30 It is obvious that various changes and modifications may be made in the details of construction and design of the above specifically described embodiment of this invention without departing from the spirit thereof, such changes and modifications being restricted only by the scope of the following 35 claims:—

Having thus described my patent, I claim:

1. In combination with an air heating device having a heated air outlet passage and a return cool air passage, a motor, a fan 40 mounted on the motor, said motor and fan being located in said heated air outlet passage, and means for by-passing a quantity of the air from the return cool air passage directly to the motor and fan for protecting the motor against injury by the hot air and for commingling the hot air with a small proportion of the returned cool air.

2. In combination with a pipeless hot air double walled furnace, a register placed above 50 the furnace in the floor of a room to be heated, a combined motor and fan disposed beneath said register, an air circulating casing disposed about said motor and exposed to the influence of said fan, and a conduit 55 communicating with the lower portion of said casing and with the interior space of the double walled furnace near the upper portion thereof.

3. In combination with an air heating device 60 having a heated air outlet opening and a return cool air passage, a motor, a fan mounted on the motor, means for yieldably suspending the motor with its fan in the hot air outlet, and means for by-passing a quantity 65 of the air from the return cool air pas-

sage directly to the motor and fan for protecting the motor against injury by the hot air and for commingling the hot air with the small proportion of the returned cool air.

4. In combination with a pipeless hot air double walled furnace, a register placed above the furnace in the floor of a room to be heated, a combined motor and fan disposed beneath said register, means for resiliently supporting said unit, an air circulating casing disposed about said motor and exposed to the influence of said fan, and a conduit 70 communicating with the lower portion of said casing and with the interior space of the double walled furnace near the upper portion thereof whereby to secure cold air.

75 In testimony whereof, I have hereunto set my hand this 19th day of January 1931.

80 JAMES L. WATERBURY.
